OF HUTCHINSON, KANSAS.

COMBINATION OIL AND GAS BURNER.

1,038,120.

Specification of Letters Patent. Patented Sept. 10, 1912.

Application filed February 10, 1912. Serial No. 676,697.

To all whom it may concern:

Be it known that I, JOHN A. GREENERT, a citizen of the United States, residing at Hutchinson, in the county of Reno and State of Kansas, have invented certain new and useful Improvements in Combination Oil and Gas Burners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to combination oil and gas burners, and has for its principal object to provide a device of that character which may be used with either oil or gas, or with both simultaneously, the device being particularly adaptable for localities where natural gas is used as fuel and where there is a probability of failure of the gas supply. In accomplishing this object I have provided the improved details of structure 20 hereinafter described and illustrated in the accompanying drawings, wherein like reference numerals refer to like parts throughout the several views, and wherein:

25 Figure I is a side elevation of a combination burner constructed according to my invention, the fire bowl of a stove or furnace being indicated to show the application of the burner. Fig. II is a central, vertical section of the burner. Fig. III is a plan view of same, the dome being in section on the line III—III Fig. II. Fig. IV is a similar view on the line IV—IV, Fig. II. Fig. V is a plan view of the diaphragm ring used in connection with the burner for concentrating the air for mixture with the oil vapor.

30 Referring more in detail to the parts: 1 designates the fire bowl of an ordinary stove or furnace having an inturned flange 2 on its inner face. Supported on the flange 2 is a diaphragm ring 3, preferably of sheet metal and adapted for entirely separating the fire bowl into upper and lower chambers. Supported on the ring 3 is a burner 35 base 4, comprising a supporting ring 5 which rests directly on the diaphragm ring, and a vertical flange 6 which rises from the ring 5 and is provided with ports 7 for the outlet of gas. At the inner periphery of 40 ring 5 is a keeper flange 8, and supported on

the base ring 5 within the flange 8 is a drum 9 preferably constructed of cast metal and having a slightly inwardly tapering upper portion. Extending radially from the drum 9 at a suitable distance above the burner base is a hood 10 having an outwardly and downwardly sloping rim 11 which is turned horizontally at its edge to rest on the base flange 6, and has a cupped rim 12 for a purpose presently set forth. At regular intervals around the drum are partitions 13 which divide the annular chamber within hood 10 into separate compartments. The hood and partitions are preferably cast integral with the drum 9 and there are preferably four of the separate compartments. Opening through an aperture 14 into each of said compartments is a supply pipe 15 which may extend down through the furnace grate (the furnace is not shown) and is adapted for supplying gas to each of said compartments separately and also for supporting the burner, as the weight of the burner is ordinarily too great to be supported on the sheet metal diaphragm. Extending around the upper end of the drum 9 is an outer circumferential cup member 16 adapted for receiving oil from the ends of the delivery branches 17 of a supply pipe 18 which latter extends down through a web 19 of the burner base and through the furnace grate to a source of supply. There are preferably two of the branches 17 which extend in opposite directions and feed the cup 16 at opposite sides of the burner. Supported in the cupped rim 12 of the hood 10 is a dome 20, the lower end of which is provided with ports 21 through which oil or oil vapor may flow into the outer portion of the rim. The dome is preferably cast and substantially semi-spherical in form, being separate from the body of the burner to facilitate installation.

45 In assembling the burner, the diaphragm is first placed on the fire bowl flange, and the burner base placed thereon with the pipe apertures registering with the apertures of the diaphragm ring. The supply pipes are then threaded into the apertures therefor in the burner base and connected with a source of supply. The drum 9 is then deposited on the burner base so that each of the supply pipes 15 will open into about the center of one of the gas compartments. The oil supply pipe is then installed,

50 55 60 65 70 75 80 85 90 95 100 105 110

and the entire device covered by the dome 20 which may rest freely in the hood rim 12.

With the parts assembled as described, gas may be used by opening the pipe 15 so that the gas is discharged into the separate compartments and thence outwardly through the ports 7 beneath the rim 12, each of the pipes 15 being provided with a suitable mixer (not shown), and the small compartments confining the gas so that it is discharged under pressure that insures a proper fuel mixture.

When oil is burned, the pipe 18 is opened, and oil flows out through the branches into the trough 16 over the edge of which it flows down the sides of the drum 9, over the head 10, and into the rim 12, through the dome ports 21. When the burner is hot, the oil will of course become vaporized before it has reached the rim 12, and the vapor will pass out through the ports 21, mix with air which enters through the center of the burner and rises through the drum 9 into contact with the curved inner surface of the dome by which it is deflected downwardly to mix with the oil vapor.

It is apparent that by running the oil supply pipe through the hood 9, and admitting fresh, cool air through said hood, the oil in the supply pipe will be kept cool until discharged into the hood trough thereby, obviating carbonizing of the oil, which carbonizing would result in stoppage of the pipes.

It is apparent that the parts of the burner are constructed to adapt the burner for the use of either oil or gas, and that the combination for the separate fuels does not materially increase the cost of the burner. It is also apparent that oil and gas may be burned simultaneously.

Having thus described my invention, what I claim as new therein and desire to secure by Letters-Patent is:—

1. A burner, comprising a vertical drum having a trough on its outer face near its

upper edge, an oil supply pipe extending through the interior of the drum, and adapted for delivering into said trough, a hood on the outside of said drum terminating in a troughed rim, and a dome covering said drum and a part of the hood, said dome having ports in its lower edge, for the purpose set forth. 50

2. A burner, comprising a vertical drum having a trough on its outer face near its upper edge, an oil supply pipe extending through the interior of the drum, and adapted for delivering into said trough, a hood on the outside of said drum terminating in a troughed rim, and a semi-circular dome covering said drum and a part of the hood, said dome having ports in its lower edge, for the purpose set forth. 60

3. A burner, comprising a base having an edge flange provided with openings, a drum fitted on said base and having a hood portion supported on said flange, said hood portion being provided with a troughed rim, means for delivering oil to the outer surface of said drum, a dome seated in said rim and covering the drum and hood, and supply pipes opening through said base into said hood. 65

4. A burner, comprising a base having an edge flange provided with openings, a drum fitted on said base and having a hood portion supported on said flange, said hood portion being provided with a troughed rim, means for delivering oil to the outer surface of said drum, a dome seated in said rim and covering the drum and hood, and supply pipes opening through said base into said hood, said hood being divided into separate compartments, substantially as set forth. 80

In testimony whereof I affix my signature in presence of two witnesses.

JOHN A. GREENERT.
